UNITED STATES PATENT OFFICE

146,372

DESIGN FOR A SHOWCASE

Stanley L. Musselman, South Orange, N. J.

Application January 15, 1946, Serial No. 125,570

Term of patent 3½ years

(CL. D80—11)

To all whom it may concern:

Be it known that I, Stanley L. Musselman, a citizen of the United States, residing at South Orange, in the State of New Jersey, have invented a new, original, and ornamental Design for Showcases, of which the following is a specification, reference being had to the accompanying drawing, forming part thereof.

The figure is a perspective view of a showcase, showing my new design.

I claim:

The ornamental design for a showcase, as shown.

STANLEY L. MUSSELMAN.
